UNITED STATES PATENT OFFICE

ELLSWORTH W. JOHNSON, OF HECTOR, MINNESOTA, ASSIGNOR TO MIDWEST MOTOR SUPPLY, OF HECTOR, MINNESOTA, A FIRM

HAT HOLDER

Application filed April 9, 1928. Serial No. 268,498.

This invention relates to a holder for hats of a simple nature which may be adapted to be used in an automobile or it may be used just as readily to hold a hat in public buildings or under church and theater seats. A feature of my invention resides in a simple means of holding a hat, the supporting means including a ring that extends around the crown of the hat and engages the brim without deflecting or bending the brim and yet holding the hat firmly in place. My holder can be attached in the automobile, particularly in closed cars so that the hat may be held up against the roof out of the way.

A feature of my invention resides in locking the holding means in place so that the hat can be held in public places without fear of it being stolen and so that it can be easily and readily removed when the owner unlocks the means which locks the holding member in place.

It is also an object of my invention to provide a holder having a spring means for holding the hat engaging ring in place to hold the hat tightly without injuring the same and in a convenient manner.

These objects together with other details and features of the invention will be more fully and clearly described and set forth in the specification and claims.

In the drawings forming part of this specification:

Figure 1 shows my hat holder attached to an automobile, only a portion of which is illustrated, in section.

Figure 2 is a perspective view of my hat holder.

Figure 3 is a plan view of the same.

Figure 4 is a detail of a portion of the same.

Figure 5 shows a portion of the hat holder with a lock arrangement.

Figure 6 illustrates my hat holder with the lock arrangement as it may be used in public buildings.

My hat holder A is designed to hold a hat B up out of the way and is primarily adapted in its simple formation to be used in conjunction with automobiles.

The holder A is formed with a brim engaging loop 10 made of wire or other suit-

able material, the ends of which are bent to provide an offset portion 11 which terminates in the ends 12 extending approximately parallel with the engaging and holding ring 10.

The ends 12 are clamped between the side members 13 and 14 by the bolt 15 and the members 13 and 14 are hinged at 16 to the bracket member 17 which is provided with a wall engaging portion 18. The portion 18 is adapted to be secured to the wall in the manner illustrated in Figures 5 and 6 and may be also secured to the rail 19 of an automobile body, as illustrated in Figure 1. The member 13 extends along away from the pivot point 16 farther than the portion 14 and is adapted to be engaged by a coil spring 20 which operates to hold the brim engaging ring or loop 10 in operative position, as illustrated in Figure 1. The dotted outline in Figure 1 shows the ring 10 pulled away from the ceiling 22 of the automobile so that the hat B can be inserted therein or removed therefrom.

In Figures 6 and 5 I have illustrated a lock cylinder 24 which is operated by the key 25. The lock cylinder 24 is adapted to lock the ends 12 and the portions 13 and 14 in the positions illustrated in Figures 5 and 6 to cause the hat loop or ring 10 to engage the brim of the hat and hold it against the wall 26 when it is desired to lock the loop against pivoting operation on the hinging point 16.

My hat holder A is designed to operate as described for holding the hat in an automobile and in its simple formation illustrated in Figures 1 and 2, no lock is required. The spring 20 holds the loop 10 in operative position to hold the hat tightly engaging the ceiling 22 of the car, or the hat holder A may be attached in any other position or convenient place in the car so that it can support a hat out of the way and prevent injury to the hat, and also hold it from blowing out of the car.

Figures 5 and 6 illustrate the locking type of my holder A and in this form the holder is more adapted for use in public places. This form of holder may be readily unlocked by a suitable key, such as 25, and the locking

mechanism, while the detail is not shown, is of ordinary well known construction so formed as to hold the holding loop 10 to press the hat brim against the wall 26 and lock it there until the lock 24 is released. Where the lock is used the spring 20 may not be necessary.

I have shown my hat holder A to be of a very desirable nature, simple, inexpensive, and a practical utility for use with automobiles.

In accordance with the patent statutes I have described the principles of operation of my hat holder and while I have endeavored to point out and represent the best embodiment thereof, it is obvious that variations and evident changes may be made within the scope of the following claims without departing from the spirit of the invention.

I claim:

- 20 1. A hat holder including, a wire ring, crossed ends formed on said ring offset from said ring, straight ends extending virtually parallel with said ring, a clamp for engaging the ends of said ring, a hinge formed in said clamp, a wall bracket extending from said hinge, and a coil spring connecting the end of said clamp with said wall bracket to urge the operation of said hat holding ring.
- 25 2. A hat holder including, a ring-like loop formed from a wire bent to provide crossed ends, a clamping plate for engaging the free ends of said wire loop, said clamping plate being pivotally secured to a second attaching plate member and a coil spring connecting the first and second plate members.
- 30 3. A hat holder comprising, a wire loop having the free ends crossed at the periphery of the loop, parallel ends extending from the crossed portion of said wire, a clamping plate for clamping the parallel ends, an attaching plate pivotally connected to said clamping plate and spring means connecting said clamping plate and said attaching plate.
- 35 4. A hat holder including, an attaching plate, a clamping plate means hingedly connected to said attaching plate and an offset wire hat holding loop formed by crossing the free ends of said wire and bending the free ends in a manner to be extended longitudinally of said clamping plate and rigidly secured thereby.
- 40 5. A hat holder including, a pair of plates hingedly connected together, one of which is adapted to form an attaching plate, the other plate having a clamping member associated therewith, a wire hat engaging loop having the free ends thereof crossed and bent to extend longitudinally of one of said plate members offset therefrom and clamped by said clamping member to extend the hat loop longitudinally from said plate member.

ELLSWORTH W. JOHNSON.
